DESIGN FOR A COMBINED BILLFOLD, PASS HOLDER, AND CHANGE PURSE

Samuel J. Smallman, New York, N. Y.

Application March 9, 1944, Serial No. 112,837

Term of patent 14 years

(Cl. D87—3)

To all whom it may concern:

Be it known that I, Samuel J. Smallman, a citizen of the United States of America, residing in New York, county of New York, and State of New York, have invented a new, original, and ornamental Design for a Combined Billfold, Pass Holder, and Change Purse, of which the following is a specification, reference being had to the accompanying drawing, forming part thereof.

Fig. 1 is a front view of a combined billfold, pass holder, and change purse showing my new design with the pass holder, which is detachable, and the change purse in closed position:

Fig. 2 is a similar view with the detachable pass holder in open position; and

Fig. 3 is a fragmentary view of the right side of the article shown in Figs. 1 and 2 with the pass holder removed and the change purse in open position.

I claim:

The ornamental design for a combined billfold, pass holder, and change purse, substantially as shown and described.

SAMUEL J. SMALLMAN.
